UNITED STATES PATENT OFFICE

128,048

DESIGN FOR A STUFFED TOY

Harry Klein, New York, N. Y.

Application April 2, 1941, Serial No. 100,099

Term of patent 3½ years

To all whom it may concern:

Be it known that I, Harry Klein, a citizen of the United States, residing at New York city, in the county of the Bronx and State of New York, have invented a new, original, and ornamental Design for a Stuffed Toy, of which the following is a specification, reference being had to the accompanying drawing, forming part thereof.

The figure is a perspective view of a stuffed toy, showing my new design.

I claim:

The ornamental design for a stuffed toy, substantially as shown.

HARRY KLEIN.
